CLAIM

The ornamental design for a multiple lamp bulb package, substantially as shown and described.

DESCRIPTION

FIG. 1 is a front perspective view of a multiple lamp bulb package showing our new design;

FIG. 2 is a side elevational view thereof, the opposite side being substantially similar in appearance;

FIG. 3 is a top plan view thereof;

FIG. 4 is a bottom plan view thereof; and

FIG. 5 is a rear elevational view thereof.

The dash lines in FIGS. 1 and 3 represent score lines.

FIG. 1

FIG. 4
